CLARENCE S. APPLAS AND WALTER T. APPLAS, OF MOLINE, ILLINOIS.

BOX-LID HOLDER.

1,265,033.

Specification of Letters Patent.

Patented May 7, 1918.

Application filed November 29, 1916. Serial No. 134,193.

To all whom it may concern:

Be it known that we, CLARENCE S. APPLAS and WALTER T. APPLAS, citizens of the United States, residing at Moline, in the county of Rock Island and State of Illinois, have invented a new and useful Box-Lid Holder, of which the following is a specification.

This invention relates to box lid holders and price markers.

The object is to provide a device for supporting the lids of cigar boxes, or the like, to exhibit the contents, in a manner to permit of closely assembling the boxes, as is usually done in showcases or upon shelves, and, at the same time, to display the price of such contents by means forming part of the device, and which may be readily changed to suit the various values of the contents.

The device is designed to simplify the construction of the lid holder and price marker shown and described in Patent No. 1,198,511, issued to C. S. Applas, September 19, 1916, by the elimination of some of the parts thereof and the modification of certain other parts, so that the improved device is capable of manufacture at a very low cost and may be applied to a box, to perform the above function, without the necessity for any care being taken or any special adjustment being required.

A full and complete understanding of the invention may be obtained from a consideration of the following detailed description, taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the claims appended hereto.

In the drawing, in which like reference numerals designate corresponding parts in each of the several figures:

Figure 1 is a side elevation of the improved box lid holder, in its applied position.

Fig. 2 is a front elevation of the same, showing the price marker in its initial position, in dotted lines.

Fig. 3 is a top plan view of the same, the box lid being in section.

Fig. 4 is a detail perspective view of the lid supporting means, the price marker being detached therefrom.

Fig. 5 is a perspective view of a slightly modified form of the invention.

In the present embodiment of our invention a single supporting plate 1 is employed, which may be readily stamped out of relatively thin sheet metal, but must, of necessity, be of sufficient stiffness and rigidity to prevent any bending or flexing in order to properly support the lid of a box, as well as to carry price indicating means to be hereinafter described.

The supporting plate 1 comprises a main body portion, provided, at its lower end, when the device is in the installed position upon a box, with an open ended, vertically disposed slot 2 adapted to fit over the rear wall 3 of an ordinary cigar box or other receptacle, as illustrated in Figs. 1 and 2 of the drawing. This slot 2 is arranged at a slight angle to the rear edge 4 of the supporting plate 1, in order that when the said plate is applied to the rear vertical wall 3 of the cigar box or other receptacle, the rear edge 4 will be arranged at an upward and outward inclination to approximate the desired angle at which the box lid 5 is to be supported.

An upwardly extending arm 6 is provided upon the supporting plate 1, and is of a width somewhat less than the width of the body portion of the plate 1, though sufficient to provide the necessary strength to support the lid 5. An eye 7 is formed at the upper end of the arm 6, preferably by bending the terminal thereof upon itself, and is in a position at right angles to the rear wall 3 of the cigar box or other receptacle.

A clamping loop 8 formed of stiff wire or other suitable material, and provided with a bearing portion 9, is swiveled in the eye 7 of the supporting plate 1, and has approximately parallel arms 10 and 11 extending from the bearing portion 9, the arm 10 being preferably somewhat longer than its opposed arm 11. The arms 10 and 11 are adapted, when the device is applied to a box, to extend inwardly at right angles to the bearing eye 7 and to embrace the rear and front sides, respectively, of the box lid,

in order to rigidly maintain the same in its desired position. The arm 10 is preferably

bent to approach its coacting arm 11, as indicated at 12 in Fig. 3, and there forms an abutment to bear against the rear face of the box lid 5; the terminal portion of the 5 said arm 10 being returned upon itself to form an eye constituting an actuating handle 13, adapted to be grasped by the hand of the operator for the purpose of swinging the supporting arms, and price marking 10 means to be described, at right angles to the plate and into and out of engagement with the lid 5.

The arm 11 is provided with a terminal eye 14, the axis of which lies parallel to the 15 axis of the eye 7, and is adapted to be engaged by a rivet 15. The rivet 15 is employed to secure price marking means 16 to the arm 11, though any other method of fastening the same may be employed.

20 The price marking means 16 is substantially the same as shown in the patent here- 25 tofore mentioned, and so needs no specific description herein. The same, however, comprises a revolving disk 17, suitably mounted to be rotated at will to expose various prices, when it is desired to change the same to adapt the device to different boxes containing cigars or other articles having different values.

30 The slightly modified form illustrated in Fig. 5 consists of the supporting plate 1, precisely the same as heretofore described, and having the lid-engaging arms 10 and 11 similarly swiveled thereto. In this form, 35 however, the price marker 16 is dispensed with, and a horizontally disposed eye 18 similar to the eye 13 is formed on the end of the arm 11, and is adapted to be grasped by the hand of the operator, the same as 40 the eye 13, to swing the device into or out of operative relation with the lid 5. In this form the arm 11, lying in front of the said lid 5, may be utilized to clamp a card 19 or other price marker on the front face of the 45 lid, and, consequently, in full view of the prospective purchaser.

That portion of the supporting plate 1 lying in rear of the vertically disposed slot 2 is somewhat elongated to form a down- 50 wardly extending arm 20, adapted to lie against the rear face of the box member 3, and the corresponding arm 21 formed on the other side of the slot 2 is of somewhat less length and fits within the box and ad- 55 jacent to the end wall 22 thereof in such a manner as to not interfere with the cigars or other articles contained therein.

From the foregoing it will be seen that 60 a device of extreme simplicity has been de- 65 vised, and which is capable of being readily applied to a cigar box or other receptacle without injury to the contents thereof for the purpose of maintaining the lid in the desired open position, at the same time dis- 65 playing the price of the contents thereof,

and permitting of placing boxes in close relation one to another within a showcase or upon a shelf, thus resulting in economy of space required for this purpose. It will also be seen that the same may be easily 70 stamped from sheet metal or other similar material, thus rendering the same capable of manufacture at an extremely low cost.

What is claimed is:-

1. A device of the character described 75 comprising a flat relatively thin plate having a slot in its end disposed angularly to the rear edge of said plate, to fit over the rear wall of a box next to the adjacent end wall thereof and against the end edge of the 80 lid for said box when open, and a substantially U-shaped clamping loop swingingly supported at the upper end of the plate to embrace the edge adjacent thereto of the lid when said loop is in said position and to 85 release the lid when in another position, the axis of movement of said loop being crosswise of said plate.

2. A device of the character described 90 comprising a flat relatively thin plate having a slot in its end disposed angularly to the rear edge of said plate, to fit over the rear wall of a box next to the adjacent end wall thereof and against the end edge of the 95 lid for said box when open, a substantially U-shaped clamping loop swingingly supported at the upper end of the plate to embrace the edge adjacent thereto of the lid when said loop is in one position and to release the lid when in another position, the 100 axis of movement of said loop being crosswise of said plate, and an eye formed from the upper end of the plate and projecting from the plane of its outer face to swingingly support the loop.

3. A device of the character described 105 comprising a flat relatively thin plate having a slot in its end disposed angularly to the rear edge of said plate, to fit over the rear wall of the box next to the adjacent end 110 wall thereof and against the end edge of the lid for said box when open, a substantially U-shaped clamping loop swingingly supported at the upper end of the plate to embrace the edge adjacent thereto of the lid 115 when said loop is in one position and to release the lid when in another position, the axis of movement of said loop being crosswise of said plate, an eye formed from the upper end of the plate and projecting from the plane of its outer face to swingingly support the loop, and display means held by said loop.

4. A device of the character described 120 comprising a flat relatively thin plate having a slot in its end forming long and short 125 arms to fit over the rear wall of a box adjacent one end wall thereof with the uppermost end portion of said plate terminating a distance above the plane of the upper 130

edges of the body of the box and in parallel relation to and against the lid for said box when open, and a resilient clamping loop swingingly supported at the upper end of 5 the plate to embrace the adjacent edge of the lid when said loop is thrown inwardly relative to the plate and for releasing the lid on the throwing of the loop outwardly from the plate.

In testimony that we claim the foregoing 10 as our own, we have hereto affixed our signatures in the presence of two witnesses.
